PIANO

Wilbur M. Day, Kenwood, Ohio, assignor to D. H. Baldwin Company, Cincinnati, Ohio, a corporation of Ohio

Filed Oct. 3, 1963, Ser. No. 76,846

Term of patent 14 years

(Cl. D56—9)

The figure is a perspective view of a piano embodying my new design.

The dominant features of the design reside in the portions shown in full lines.

The piano legs shown in full lines are mirror images of each other.

I claim:

The ornamental design for a piano, substantially as shown and described.
